FULL FASHIONED KNITTING MACHINE

Karl Richard Lieberknecht, Oberlungwitz, Germany, assignor to Kaliö Inc., New York, N. Y., a Corporation of New York

Application May 26, 1932, Serial No. 613,597, and in Germany April 4, 1932

5 Claims. (Cl. 66—82)

This invention relates to full fashioned knitting machines particularly of the Cotton type.

Its primary object is the provision of a new and improved mechanism for the operation of the slur cocks, thread carriers, and other parts requiring a reciprocating motion, which is simple, effective, and inexpensive, and which may be duplicated as many times as desired in the various knitting units of which the machine is composed without introducing troublesome complications or involving much expense.

Up to the present time flat knitting machines, and particularly those of the Cotton type, have been provided with a coulier motion whereby the rotary motion of a cam shaft is translated into the reciprocating motion required by the slur cocks and thread carriers.

The coulier motion is well known for these purposes and comprises essentially a short shaft positioned at right angles to the main cam shaft and driven therefrom through bevel gears and having fixed thereon a coulier cam which cooperates with a suitable pitman and connecting rod, the latter ultimately connecting with the slur cocks and thread carriers. Ordinarily a single coulier motion is provided positioned approximately midway the length of the machine, and from it the movement of even the most remote sections of the machine is controlled.

It has been suggested that the coulier cam shaft might be provided with several cams for the several reciprocatory movements required but this would be impossible without increasing the width of the machine to provide space for a longer shaft and would not eliminate the undesirable feature that the power is applied to various parts which must operate with extreme accuracy from a point more or less remote. The suggestion has also been advanced that this last difficulty might be overcome by equipping the machine with several coulier motions, each controlling one or more sections of the machine. Two serious objections to this idea are the large expense and lack of space.

By means of my invention I solve these problems in a relatively inexpensive and most convenient manner by eliminating the ordinary bevel gear coulier motion entirely and providing a special auxiliary cam shaft running the entire length of the machine and positioned preferably at the back of the machine where ample space is available without disturbing other mechanisms.

Upon this as many coulier cams and as many

other cams as desired may be positioned close to the parts to which power is to be applied.

One form of my invention is illustrated by the accompanying drawings in which—

Figure 1 is a partial plan view of a flat knitting machine equipped with my invention; 60

Fig. 2 is a similar front elevation of the same machine;

Fig. 3 is a cross-section at line A—A of Fig. 2;

Fig. 4 is a cross-section at line B—B of Fig. 2; 65 and, Figs. 5 and 6 are a diagrammatic side elevation and end elevation, respectively, of one form of cam and cam roller which may be employed in my invention.

The machine is provided with the usual main cam shaft 2. In addition, it has an auxiliary cam shaft 1, preferably positioned as heretofore suggested at the back of the machine where the majority of the parts operated from it are located, and driven from the main cam shaft in 75 any suitable way, such as by sprockets 3 and 5 and chain 4. The speed of auxiliary shaft 1 should be one-half that of the main cam shaft 2, as is now the case with the usual coulier shaft, to secure one complete operative cycle of 80 the parts controlled from the auxiliary shaft for each two revolutions of the main cam shaft 2.

Upon auxiliary cam shaft 1 is fixed the coulier cam 6 which imparts reciprocatory motion to pitman 9 through engagement with rollers 7 and 8 85 carried thereby. The upper end of pitman 9 is provided with a rack 10 which engages with the pinion 11 keyed to a shaft 13 mounted in suitable bearings upon the frame of the machine by means of a bracket 13a. Shaft 13 also carries a second pinion 12 which meshes with a rack 14 attached to rod 15 by which the slur cocks are carried. Rotation of coulier cam 6 will thus cause slur cock rack 14 to reciprocate back and forth once for each two revolutions of the main cam shaft 2. 95

As many coulier cams as desired may be provided on auxiliary shaft 1 so that the application of power to the slur cocks of the various sections of the machines may be centralized or applied as close to the operating parts as desired. 100

Similarly, I provide on the same auxiliary cam shaft means for imparting a reciprocating motion to the main thread carrier rods. This consists of a cam 16, a pitman 19 similar to coulier pitman 9, and provided with similar rollers 17 and 18, and a rack 20. Rack 20 engages with pinion 21 on short shaft 23 which also carries pinion 22. This pinion meshes with rack 110

24 attached to rod 25 which carries the friction boxes 25^a of the main thread carrier rods. As in the case of the coulier motion, rotation of cam 16 causes the main thread carrier rod to 5 reciprocate in the well known manner. Additional cams may be provided on auxiliary cam shaft 1 for operating other reciprocating parts. For example, in the machine illustrated in the drawings, cams 26 and 27 are employed to im- 10 part reciprocating motion to thread carrier rods which travel less than the full width of the fabric. Cam 26 functions through lever 28 and link 30 to operate bell crank 32, which in turn reciprocates friction rod 34 which carries the 15 auxiliary thread carrier friction box 34^a. Similarly, cam 27 functions through lever 29, link 31, and bell crank 32 to oscillate friction rod 35 carrying friction boxes 35^a.

The actual length of travel of carrier rods 20 having less than full width stroke may be varied by providing the carrier cams with wide tapered faces by means of which a greater or lesser amount of movement may be given to the connecting parts and consequently to the thread 25 carriers by shifting the follower rollers to different sections of the cam faces. This may be done automatically from the narrowing mechanism, manually or in any other desired way. A suitable cam of this sort is shown at 40 in 30 Fig. 5 having a tapered cam surface 41 which coacts with cam roller 42 to rock operating lever 30. If desired, this sort of cam may be substituted for cams 26 and 27 (Fig. 2). The amount of rock imparted to arm 30 may be 35 varied by manually sliding roller 42 on shaft 43 by any suitable means, such as forked arm 44, to the proper part of the cam surface and fastening it there by nut 46. Shaft 47, which like shaft 42 is fixed to lever 30, serves as a 40 guide for the roller and arm 44 and also cooperates with nut 46 to lock the roller at the desired point.

The several motions obtained, as described, 45 from auxiliary cam shaft 1 are used only during the knitting cycle. During the narrowing operation they must not occur. Consequently a clutch mechanism must be provided whereby auxiliary cam shaft 1 will be thrown out of 50 action during the narrowing operation. For example, gear 3 may be loosely mounted on main cam shaft 2, means (such as a holder 36) being provided to prevent longitudinal movement. From the side of gear 3 projects a pin 37 adapted to engage with a pin 38 on the main cam 55 shaft 2. When these two pins are engaged gear 3 is locked to cam shaft 2 and will be driven thereby. When narrowing is to take place gear 3 is released from cam shaft 2 by disengaging pins 37 and 38 through the automatic longitudinal shifting to the left of cam shaft 2, which 60 may be accomplished by well known means, such as shogging cams.

By this invention reciprocating motion for as 65 many parts as desired may be obtained from a single auxiliary cam shaft and the generating mechanism may be positioned on this shaft in the locations most convenient and desirable for their respective purposes. The difficulties result-

ing from the location of operating cams at remote points (as in the case of the usual single coulier motion) are eliminated and a much more convenient, flexible and generally improved mechanical arrangement is made possible without altering or disturbing the arrangement of other parts or enlarging the machine and at relatively low cost.

In addition, the use of separate mechanisms for operating the slur cocks of the main and reinforcing thread carriers instead of operating all of these parts from a single coulier cam, as is the present common practice, makes it possible to operate each of these parts at a different speed from the others which is sometimes advantageous. The description heretofore given has been limited for the sake of brevity to a single mechanism for each of the motions which of course would provide for but a single speed for each one.

What I seek to secure by United States Letters Patent is:

1. A flat knitting machine having a main cam shaft and an auxiliary cam shaft, said auxiliary cam shaft having a cam thereon, a pitman engaging with said cam, a rack on said pitman, a pinion shaft, a pinion thereon meshing with said pitman rack, a second pinion on said pinion shaft, a slur cock, a rack associated with said slur cock and meshing with said second pinion, and means for rotating said auxiliary cam shaft 10 at half the speed of the main cam shaft.

2. A flat knitting machine having a main cam shaft and an auxiliary cam shaft, a cam on said auxiliary cam shaft, a cam roller engaging said cam, a bell crank, a friction rod and a link connecting said roller to one arm of the bell crank, the other arm of which engages with the friction rod.

3. A flat knitting machine having a main cam shaft and an auxiliary cam shaft, a plurality of 11 cams on said auxiliary cam shaft, an equal number of cam rollers one engaging each cam, a bell crank, a friction rod and a link connecting each roller to one arm of the bell crank, the other arm of which engages with the friction rod.

4. A flat knitting machine having slur cocks, main thread carriers, reinforcing thread carriers and an auxiliary cam shaft parallel to the main cam shaft provided with separate cams for operating the slur cocks, main thread carriers and reinforcing thread carriers, means for rotating said auxiliary cam shaft at half the speed of the main cam shaft, and means for disengaging said auxiliary cam shaft from its driving means.

5. A flat knitting machine having slur cocks, main thread carriers and reinforcing thread carriers, a main cam shaft and an auxiliary cam shaft parallel thereto, separate means for operating the slur cocks, main thread carriers, and reinforcing thread carriers, separate actuating means for each of these operating means, each consisting of a cam, a roller engaging therewith, the cam which actuates the reinforcing thread carrier operating means having a longitudinally tapered face, and means for shifting the cam roller engaging therewith to different parts of said tapered face.

KARL RICHARD LIEBERKNECHT.
